NEEDLE.

1,078,955.

Specification of Letters Patent.

Patented Nov. 18, 1913.

Application filed December 23, 1908. Serial No. 468,905.

To all whom it may concern:

Be it known that I, JOHN R. REYNOLDS, a citizen of the United States, residing at Hartford, county of Hartford, and State of Connecticut, have invented certain new and useful Improvements in Needles, fully described and represented in the following specification and the accompanying drawings, forming a part of the same.

10 This invention relates to certain improvements in sewing machine needles.

It has been customary to use curved needles with a certain class of sewing machines, and particularly with book sewing machines, the curved needles employed in such machines having usually had a curved body portion and a straight shank integral with the body portion and lying at an angle thereto, the shank extending toward the curve of the body portion. Such needles, while they have been reduced in size at and near the point, have been of substantially the same size throughout the shank and the major part of the body portion. There has, however, of late years, especially in certain classes of work done on book sewing machines, been a considerable increase in the number of pages which form the signature, these pages, as a rule, being provided by

25 increasing the number of folds in the signature, though, in certain cases, the pages are increased by introducing folded inset sheets. In either case, the strains set up upon the needles of book sewing machines increase, of course, as the number of folds of paper through which the needles must pass increase. Further, in sewing books by machinery, the perforations through which the thread is passed by the needle should be

30 as small as possible for the reason that if the perforations are large they present an unsightly appearance when the book is opened, this being particularly true of that class of books known as flexible bound books, which open so widely as to disclose the fold in the signature. Further, in binding books, as is well known, the entire back of the book, before the cover is put on, is heavily smeared with glue, and, if the perforations through

40 which the thread passes are large, the glue will penetrate through them and disfigure the inside of the book, this being particularly true of books in which the paper used is heavy or is glazed. For these reasons, it

45 50 55 is not feasible to meet the increasing strains

to which the needles are subjected by reason of the increased number of sheets in the signature to be sewn, by making the needles from wire of larger gage, because it is evident if the diameter of the needles is increased, the size of the perforations in the signatures must be necessarily increased. Further, in book sewing machines, the body portion of the needles is usually supported during the sewing operation by a needle 60 guide. Increase in the size of the needles would, therefore, necessitate a corresponding increase in the size of the guides which would involve the partial reconstruction at least of the large number of machines on 65 70 the market if they are to be adapted for sewing signatures formed by a large number of sheets.

The present invention has for its object to produce an improved needle which shall 75 have the metal contained therein so disposed as to meet the strains set up on it by the increased number of sheets in the signature, and to effect this without increasing the size of the body portion of the needle or that 80 portion of the needle which passes through the paper.

With this and other objects in view, the invention consists in a certain improved construction which will be fully described 85 and specifically pointed out.

Referring to the accompanying drawings—Figure 1 represents a side elevation of the improved needle, the view being twice actual size. Fig. 2 is a section on the line 2—2 of Fig. 1. Fig. 3 is a section on the line 3—3 of Fig. 1. Fig. 4 is a view of the blank from which the needle is formed. Fig. 5 is a view of the blank after it has been grooved, the thread carrying 90 eye formed therein, and the shank bent to form the attaching eye, the side of the blank which is nearest the observer being that which forms the inner side of the needle, as shown in Fig. 1. Fig. 6 is a view 95 100 of the blank shown in Fig. 5, the blank being turned at right angles to the position shown in that figure.

Referring to the drawings, the needle illustrated comprises a body portion 1 and a shank 2. This shank is integral with the body portion, it being formed by bending the stock or blank from which the needle is made, so that the shank lies toward the 105 curve of the body portion, as shown in the 110

figure. The shank may be further bent to form a large loop or eye, indicated at 3. The body may be provided with a thread carrying groove 4, as shown in Fig. 3, and indicated in dotted lines in Figs. 5 and 6, and will have the usual eye 7 formed therein.

It will be observed that the body portion of the needle, while it is tapered to form the point, is of substantially the same size throughout but that the shank is considerably heavier than the body portion. This is apparent not only from the construction shown in Fig. 1 but from the appearance of the blank, as illustrated in Figs. 4 and 6. In these figures, it will be seen that the shank part of the blank increases in size abruptly, this increase in size beginning at the point which is to form the bend between the shank and the body portion. The shank therefore is made to contain an increased volume of metal, so that it may withstand the strains set up on it and at the same time this is accomplished without increasing the size of the body portion of the needle. To further increase the strength of the shank of the needle, this part may be flattened, as shown in Fig. 2, and this flattening may, if desired, be continued through the body portion of the needle. By this

construction, the needle is greatly strengthened and this is accomplished without increasing the size of the body of the needle. The perforations through which the needle passes will, therefore, not be increased in size. Further, needles made as described will pass through the supporting needle guides ordinarily used on book-sewing machines at present upon the market, so that these needles may be used with such machines without any change in the construction of the machines.

What is claimed is:—

A curved needle for book sewing machines comprising a curved body portion and a straight shank extending toward the curved body portion and formed integrally therewith, the shank including the bend which connects it to the body portion being of increased size as compared with the body portion, the shank and body portion being flattened.

In testimony whereof, I have hereunto set my hand, in the presence of two subscribing witnesses.

JOHN R. REYNOLDS.
